UNITED STATES PATENT OFFICE.

ERWIN B. PHILIPS, OF STRATFORD, CONNECTICUT.

DESIGN FOR A BOX.

56,306.

Specification for Design.

Patented Sept. 14, 1920.

Application filed April 21, 1920. Serial No. 375,635. Term of patent 14 years.

To all whom it may concern:

Be it known that I, ERWIN B. PHILIPS, a citizen of the United States, residing at Stratford, in the county of Fairfield, State of Connecticut, have invented a new, original, and ornamental Design for a Box, of which the following is a specification, reference being had to the accompanying drawing, forming part thereof.

Figure 1 is a view in perspective showing the top, one side and one end of the box.

Fig. 2 is a view in perspective showing the bottom, the other side and the other end of the box.

The top 1 has the raised panels 2 semi-circular at their ends 3 and merging at their opposite ends into the central rectangular panel 4 of greater elevation than the panels 2. The ends of the box present the curved projecting portions 5. The sides 6 of the box are flat. The bottom 7 of the box presents the long central raised panel 8 with semi-circular ends 9 and the rectangular sections 10.

I claim:

The ornamental design for a box as shown and described.

ERWIN B. PHILIPS.
